(57) **CLAIM**

The ornamental design for an RV camper slide-out cleaning attachment, as shown and described.

DESCRIPTION

FIG. 1 is a top-front-left perspective view of an RV camper slide-out cleaning attachment showing my new design; FIG. 2 is a bottom-rear-right perspective view thereof; FIG. 3 is a front elevational view thereof; FIG. 4 is a rear elevational view thereof; FIG. 5 is a left-side elevational view thereof; FIG. 6 is a right-side elevational view thereof; FIG. 7 is a top plan view thereof; FIG. 8 is a bottom plan view thereof; FIG. 9 is a section view taken along line 9-9 in FIG. 6; FIG. 10 is a detail view of area 10 in FIG. 9; FIG. 11 is a detail view of area 11 in FIG. 4; FIG. 12 is a front elevational view of a second embodiment of an RV camper slide-out cleaning attachment shown broken away for indeterminate length, that being the only difference from the embodiment shown in FIGS. 1 through 11; and,

FIG. 13 is a top-front-left perspective view of the present invention, wherein the present invention is depicted in an operable configuration.

The dashed line showing a broom head and handle in FIG. 13 is included for the purpose of illustrating environmental structure and forms no part of the claimed design. Further, the slide-out cleaning attachment is shown with a symbolic break in its length. The appearance of any portion of the article between the break lines forms no part of the claimed design.
